UNITED STATES PATENT OFFICE.

WILLIAM PATON THOMSON, OF FOREST HILLS, AND CLARKSON A. DISBROW, OF NEW ROCHELLE, NEW YORK, ASSIGNEES TO THE RAIL JOINT COMPANY, OF NEW YORK, N. Y., A CORPORATION OF NEW YORK.

TRACK LINER.

Application filed April 20, 1922. Serial No. 555,700.

To all whom it may concern:

Be it known that we, WILLIAM PATON THOMSON and CLARKSON A. DISBROW, citizens of the United States, respectively, residing at Forest Hills and New Rochelle, in the counties of Queens and Westchester and State of New York, respectively, have invented certain new and useful Improvements in Track Liners, of which the following is a specification.

This invention relates to a novel track lining device having for its primary object a simple and economical tool meeting the practical requirements and susceptible of being operated in a safe and expeditious manner with a minimum amount of labor.

The relining of railroad track is an operation which is usually accomplished with the ordinary crowbar or so-called lining bar, one man to each bar, and, under some conditions of ballast and tightness of rail and other factors entering into the difficulties of operation, it is not infrequently the case that from eight to fourteen men are required for that work and the average section gang has not a sufficient number of men for the purpose. Accordingly, it is the customary practice for several section gangs to join forces when the resurfacing and relining of track is required, and that practice of course is objectionable from an organization standpoint.

Therefore, it is one of the objects of the present invention to provide a track lining device that will reduce to a minimum the labor required for resurfacing and relining track, and, at the same time a device which can be readily manufactured, of a minimum number of parts, and which can be used with entire safety from the outside of the track, as distinguished from track tools of the kind which are unsafely employed between the rails of the track.

Accordingly, a distinctive object of the invention is to provide a track lining device capable of being used at the outside of a track and possessing two very important characteristics, one of which is that of having a readily variable leverage to easily overcome whatever resistance may be offered by the out-of-line track to resuming its normal position, and the other of which is the capacity to "throw" the out-of-line track without appreciable lifting thereof. In that respect the present invention dis-

tinguishes from all types of track lining devices heretofore employed, especially those made on the lifting jack principle. In this connection it should be observed that it is important in the operation of a device of this kind that the lifting action shall be practically negligible because a section of railroad track, which for any reason has moved out of line under force or otherwise, has usually also become out of surface so that it is necessary to both resurface and re-line such track. The resurfacing is usually done first, partly because when track is out of surface it may appear to be out of line, and therefore the lining can be done more accurately after the track has been resurfaced; and after having been resurfaced it is desirable that, in "throwing" the track, it shall not be substantially lifted, otherwise particles of ballast might fall beneath the lifted ties and cause "high spots" in the track.

In addition to the special objects noted the invention also has in view a track lining device which is more or less automatic in its action in seating or anchoring itself in the ballast, thereby obviating the necessity of a special stand, base or seat, in the nature of an abutment for the device to bear against, while at the same time obtaining a positioning of the device in the ballast that will prevent any appreciable lifting force being exerted against the rail base, causing defective track as above referred to.

A further object of the invention is to provide a device that offers no obstruction to traffic, or, in other words, will fall to an out-of-the-way position in case it is left in the track, thereby eliminating the danger incident to a passing train striking the same.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which—

Figure 1 is a single line diagrammatic view illustrating a railroad track in which a part thereof has become out of line and requires relining; the full lines designating

the out of line track and the dotted lines indicating the track set to normal.

Figure 2 is a diagrammatic sectional view of a railroad track showing the application of the improved liner with the latter in an initial position.

Figure 3 is a view similar to Figure 2 showing the device having found its seat in the ballast and occupying a position ready to throw or shift the track.

Figure 4 is a similar view illustrating the relative position occupied by the parts of the liner when it has thrown the track to line.

Figure 5 is an elevational view illustrating the adaptability of the device for use with a conventional track tool, such as a claw bar or other special bar having a cam formation admitting the use of such tool.

Figure 6 is a side elevation of the device in the knock-down condition which it may assume to facilitate carrying about.

Figure 7 is a view of the claw end of the device.

Figure 8 is a top plan view of the device with the parts in the position shown in Figure 6.

Figure 9 is a cross sectional view on the line 9—9 of Fig. 6.

Figure 10 is a detail end view of the camming member.

Figure 11 is a detail view of the other end of the camming member.

Figure 12 is a top plan view of the camming member.

Figure 13 is a detail view illustrating a modification of the device for lowering the pivotal point of the rail lever and providing a plurality of downwardly projecting anchoring projections for engagement with the ballast.

Similar reference characters designate similar parts throughout the several figures of the drawings.

The improved track lining device is susceptible of economical embodiment in a practical and commercial form and may be manufactured in various ways and from different materials, such for instance as being made of either malleable iron or pressed steel, but in all forms of construction the essential structural features which contribute to the successful and practical operation of the device will remain unchanged.

The principal features of the device are a base A having a suitable anchoring element B, a rail-bearing member or lever C, and an operating member D, which operating member may be of the cam type or its equivalent and cooperating with the base and with the bearing member or lever C to effect the necessary movement of the latter. These instrumentalities may be conveniently correlated in a device that may be readily handled or carried by a workman and when in

actual use has the additional important advantage of automatically collapsing when the operator withdraws the operating member D, as for instance when he retreats from the trackway to avoid the passing train. Thus, the device is of a design that provides clearance from hanging parts of a train, and at the same time can be left in place when a train is passing so that the workman can quickly resume his work without having to replace any part except the operating member.

Referring to the details of construction of the example or practical embodiment of the track liner shown in the drawings, it will be seen that the base A may consist of a relatively flat body 1 preferably provided with suitable reinforcement throughout its underside, as for instance the longitudinal and transverse reinforcing ribs or their equivalents 2 and, if desired, may be conveniently provided at one end with an opening or hand hold 3 for carrying purposes. This base is specially designed so that it can be readily employed in loose or yielding ballast and has an automatic self-seating function.

In the present form of the device these results are obtained by providing the base with anchoring means of a suitable construction, as for instance forming what may be termed the front end of the base with an anchoring element or claw B of spade-like form, as suggested in Figures 7 and 9, to present a penetrating point 4 which assists in the device seeking its own embedment in the ballast. Also the anchoring element or claw B is so disposed with relation to the main body of the base that it operates, in seeking its embedment in the ballast, to tilt the base from the horizontal so that the action of the rail-bearing member or lever C will not include an appreciable lifting movement. This may be accomplished by other means than the anchoring element or claw B, but, in the preferable construction shown, said anchoring element or claw is curved or inclined downwardly from the flat plane of the body 1, as clearly shown in the general view 2, 3 and 4 and other figures of the drawings.

The rail-bearing member or lever C is pivoted at one end as at 5 to the base adjacent the front or claw end thereof. The pivotal mounting may be provided for in any suitable way, for example forming the base and its front end portion with upstanding ears 6 between which one end of the lever C is pivoted, or, as suggested in Figure 13, the ears 6^a may be reversed and depressed below the base at the underside thereof and given a substantially pointed shape so that the same will act as additional or supplemental anchoring projections to cooperate with the anchoring element or claw.

B to increase the anchoring hold of the device in the ballast to better overcome the resistance to the throwing of the track.

The rail-bearing member or lever C may 5 be of any desired cross sectional shape to provide the desired strength necessary for moving the load imposed thereon, but a practical form of this lever is shown in Figure 9 of the drawings in which the same is 10 preferably provided at its underside with a guiding channel 7 for receiving the peripheral portion 8 of the operating member or cam D. The effect of this construction is to better maintain the operating relation be- 15 tween the lever and the cam, avoiding relative lateral movement and consequent strain on the pivot.

The operating member or device D is preferably in the form of a cam fulcrumed at 20 one end of its arc, and it may therefore be an ordinary track tool, such as the claw-bar shown in Figure 5 of the drawings, such claw-bar being designated in that figure of the drawings by the reference number 9 25 and having at one end the usual cam formation 10 presenting a pointed laterally deflected terminal 11 which may be fulcrumed behind and against any one of the series of upstanding bearing shoulders 12 formed 30 upon the upper side of the base 1 of the device. However, as a part of the manufactured article it is preferable to have the operating member or cam D of the special design shown in the Figures 10, 11 and 12 35 of the drawings.

From the above figures it will be seen that the peripheral portion 8 of the cam device D is preferably of flaring width at the ends thereof, whereby the front end 13 provides 40 the relatively extended fulcruming edge 14 for engaging with the shoulders 12 of the base. The opposite or rear end 15 of the cam is notched or cut away, as indicated at 45 16, to provide clearance for the handle member which fits into the socket 17 at the underside of the cam body. As will be seen from the drawings, this socket is preferably formed with several diameters to facilitate the receiving of different types of operating 50 handles, such for instance as one end of an ordinary crow-bar or the handle of a claw-bar or the like.

To facilitate the carrying or transportation of the complete device in a compact and 55 convenient manner a suitable loop or bail 18 may be used to tie or clamp the base and lever together. In that connection it may be observed that the cam device D may be clamped between the lever and the base when 60 the parts are thus held together by the bail, so as to hold all of the parts compactly assembled, and thereby facilitate handling.

In using the device the point or nose 4 of 65 the anchoring claw B is placed in the ballast at a suitable position beneath the rail base,

as shown in Figure 2 for example. The cam D or other means for shifting the lever C may then be placed against a convenient abutment shoulder 12 on the base so that upon manipulation of the cam the lever will 70 be moved into engagement with an edge of the rail flange. The initial movement of the cam or its equivalent against the lever will have the effect of causing the claw B to firmly embed or seat itself in the ballast. 75 As the ballast is compressed to the point where it may be utilized as an effective and solid base against which the device may work, the cam D is shifted from one shoulder to another toward the claw end of the 80 base so that the lever C is gradually brought to a correspondingly steeper pitch or incline with reference to the rail base, thereby having the effect of causing the pressure exerted by the lever to be more and more nearly 85 horizontal than vertical to provide the desired shifting rather than lifting of the rail. The continued manipulation of the cam to press the lever C against the edge of the rail flange, therefore, has the effect of gradually shifting the entire trackway laterally or horizontally, in the manner indicated in Figure 4, without lifting the track to permit ballast to fall beneath the ties. 90

By the use of the claw B, the necessity of 95 preparing a special base or foundation for the fulcruming end of the lever C to work against is eliminated, and much time is saved thereby.

Also by reason of the provision of the 100 several abutment shoulders on the base, the cam may be set to any one of a number of desired positions to insure, first, the proper seating of the base before the rail is shifted and, second, shifting the track after a firm 105 foundation or abutment has been provided.

Without further description it is thought that the features and advantages of the improvement will be readily apparent to those skilled in the art, and it will of course be understood that changes in the form, proportion and minor details of construction may be resorted to without departing from the spirit of the invention or scope of the appended claims. 110

We claim:

1. A track lining device including a base and track throwing means carried thereby, said base having a ballast-engaging bottom surface and provided with anchoring means rendered increasingly effective as the force of the track throwing means is applied to the rail. 120

2. A track lining device including a base having a ballast-engaging bottom surface and provided at an end with a terminal anchoring member, a track throwing member pivoted to the base and an actuator fitted between the base and the lever to actuate the latter. 125

3. A track lining device including a base having a ballast-engaging bottom surface and also provided at one end with a downwardly curving ballast-engaging and ⁵ bedding tip and track throwing means connected with the base and arranged to exert a force thereon at substantially right angles to said tip.
4. A track lining device including a base ¹⁰ having a ballast-engaging bottom surface and a deflected forward end, a track throwing lever pivoted to the body and means arranged between the free portion of the lever and the body and adapted to move the lever with reference to the body.
5. A track lining device including a base having anchoring means and a plurality of bearings thereon, a rail-bearing lever carried by the base, and an operating lever ²⁰ adapted to be successively fulcrumed on said several bearings and operating against said lever.
6. A track lining device including a base, a movable rail-bearing member carried by ²⁵ the base and a cam adapted to be progressively fulcrumed on the base and having a progressive engagement with said rail-bearing member.
7. A track lining device including a body ³⁰ having an offset ballast engaging and pointed forward end, a track throwing lever pivoted to the body, and means arranged between the free end of the lever and the body and adapted to move the lever with reference to the body.
8. A track lining device including a body having an offset ballast engaging claw, a ⁴⁰ track throwing lever pivoted to the body, and a cam arranged between the free end of the lever and the body and adapted to move the lever with reference to the body.
9. A track lining device including a body having an offset ballast engaging claw, a ⁴⁵ track throwing lever pivoted to the body, and a cam arranged between the free end of the lever and the body and having an interlocking engagement with the latter, said cam being adapted to be moved to thereby impart movement to the lever.
- 50 10. A track lining device including a body having an offset ballast-engaging claw and a plurality of abutment shoulders thereon, a track throwing lever pivoted to said body, and a cam adapted to detachably interlock with said abutment shoulders and engage ⁵⁵ with said lever.
11. A track lining device including a body adapted to rest upon the ballast and having an offset claw for engaging in the ballast substantially at right angles to the ⁶⁰ body, a throwing lever pivotally mounted on said body adjacent the claw, and a cam adapted to engage with the body and also with the lever to operate the latter.
12. A track lining device including a body having an offset ballast engaging claw, a plurality of upstanding abutment shoulders formed on the upper face of the body, bearing eyes formed at one end of the series of ⁷⁰ abutment shoulders, a lever pivoted in said bearing eyes, a cam having a bar receiving socket and a working face adapted to engage with the lever, and said cam also having a fulcruming rib for detachably interlocking with one of the shoulders on the body. ⁷⁵
13. A track lining device including a body having an offset ballast embedding claw, a throwing lever pivoted to the body, and a detachable device arranged between the lever and the body for actuating the lever ⁸⁰ and adapted to detachably interlock with the body.
14. A track lining device including a body, a track throwing lever pivoted thereto, a cam for operating the lever adapted to be arranged between the lever and the body, and means for holding the lever in a fixed position with reference to the body to clamp the cam between the lever and the body and thereby permit the entire device to be carried as a unit. ⁸⁵
- In testimony whereof we hereunto affix our signatures in the presence of two witnesses.
